INTERNAL COMBUSTION ENGINE
Frederick R. Peterson, W. 1414 Mallon,
Spokane, Wash.
Filed Aug. 13, 1962, Ser. No. 216,367
9 Claims. (Cl. 123—18)

My invention is directed to an improved twin cycle internal combustion engine. One purpose of my invention is to provide such an engine wherein two pistons are connected together to rock as one unit about a central axis and cooperate with a cylinder to fire alternately and use the power stroke of one piston to effect the exhaust stroke of the other piston and at the same time, to mix and compress the next fuel charge for the first piston.

It is also a purpose of my invention to provide a two piston-cylinder construction wherein the two pistons oscillate within the cylinder on the axis of the cylinder and the flow of the explosive fuel-air mixture to the explosion chamber is through end plates that close the ends of the cylinder.

A further purpose of the invention is to provide an engine having the characteristics referred to in the preceding paragraph with means whereby the explosion stroke compresses the next fuel-air charge, and the piston is so shaped as to direct the charge into the explosion chamber away from the exhaust parts so the explosion chamber is efficiently cleared of spent gas with a minimum loss of unburned fuel.

The purposes and advantages of the invention will appear more fully from the following description and the accompanying drawings illustrating a preferred form of the invention. The drawings and description are illustrative only, however, and are not intended to limit the invention except insofar as it is limited by the claim.

In the drawings:

FIGURE 1 is an end view of the engine;

FIGURE 2 is an end view similar to FIGURE 1, but looking at the other end of the engine with parts of the housing broken away;

FIGURE 3 is an end view of the engine cylinder and base only, with the nearest end plate removed, the direction of the view being the same as in FIGURE 1;

FIGURE 4 is a plan sectional view taken on the line 4—4 of FIGURE 3;

FIGURE 5 is a sectional view on the line 5—5 of FIGURE 4 with parts removed;

FIGURE 6 is an interior face view of one end plate of the cylinder;

FIGURE 7 is an interior face view of the other end plate of the cylinder;

FIGURE 8 is a sectional view on the line 8—8 of FIGURE 5;

FIGURE 9 is a fragmentary sectional view taken substantially along the line 9—9 of FIGURE 6;

FIGURE 10 is a fragmentary sectional view on an enlarged scale showing the details of the sealing means used; and

FIGURE 11 is an enlarged fragmentary sectional view on the line 11—11 of FIGURE 3.

Referring now to the drawings, my engine embodies a casing or cylinder 1 with a base 2 that bolts to a base frame 3. An oil pan 4 is bolted to the frame 3. The casting 1 has a cylindrical inner surface and is closed at its ends by end plates 5 and 6 that will be described more in detail later. A piston unit comprises a hollow shaft 7 and two pistons 8 and 9. One end of the shaft 7 is journaled in the end plate 5 and the other end thereof extends through the end plate 6. A drive arm 10 is fixed to the projecting portion 7a of the shaft 7. The arm 10 has its outer end pivotally connected to a connecting rod 11 which extends to the offset portion 12 of a crank shaft

2

14. The shaft 7 is rocked to and fro as will be later explained and the arm 10 is of such length that the rocking stroke of the arm 10 in one direction will turn the crank shaft 14 a half turn. The crank shaft 14 has a drive gear 13 thereon driving a distributor shaft 15 for the distributor 16. The crank shaft also has cam means 17 for actuating push rods 18 and 19 that open two fuel inlet valves 30.

A top block 20 and a bottom block 21 are fitted within the cylinder. The block 20 has its corners recessed at 22 and 23 to form two pockets. Two spark plugs 24 and 25 are mounted in the cylinder 1 to project into these pockets.

Fuel as a combustible gas is obtained in any conventional manner, such as by mixing air and gasoline from a carburetor C. This fuel is introduced from a fuel inlet manifold 26 in the lower block 21 to two valve units 27 and 28. The valve units are mirror images of each other. Each unit comprises a shell 29 that is fastened to the block 21. Opposite the block 21 this shell has a valve seat 31 for a valve 30. This valve has a stem 32 extending into the shell through a spring 33 and against one of the push rods 18 or 19, which are slidably mounted in the block 21. The stem 32 has a spring cup 34 at its lower end so that the spring 33 keeps the valve 30 closed except when it is raised by the push rod.

25 The piston 8 and 9 are provided with recesses 8a and 9a into which the valve units 27 and 28 project when the pistons are in their lowermost positions. For access to the springs 33 each shell 29 has one side 29a removable.

The end plate 5 has a chamber 5a therein which opens 30 into the space between the block 21 and the piston 8 through passages 35 in the inner wall of the plate 5. This wall also has outlet passages 36 that open into the space 8b above the piston 8 when the piston 8 is in its lower position. The end plate 5 has a chamber 5b similar to 35 the chamber 5a. The chamber 5b opens into the space between the block 21 and the piston 9 through the passages 37. There are outlet passages 38 that open from the chamber 5b into the space 9b above the piston 9 when this piston is in its lowermost position.

40 Each of the valve units 27 and 28 has its valve 30 raised when the respective piston 8 or 9 is moving upward so that a charge of fuel is drawn into the recess 8a or 9a as the piston having that recess moves up. Then before the piston moves down, the corresponding valve 30 closes 45 so that the fuel charge just drawn in is compressed as the piston moves down. There will be some residual fuel left in the space around the valve units and in the chambers 5a and 5b when the passages 36 and 38 are closed by upward movement of the respective pistons 8 and 9. 50 This residual fuel is mixed with the next charge drawn in. Thus good mixing and preheating of the fuel charge is obtained.

The end plate 6 has exhaust ports 40 therein which open 55 from the firing chamber or space 8b into a passage 41 in the plate 6. This passage 41 leads to the periphery of the plate 6 where an exhaust gas tube 42 is attached. The plate 6 also has exhaust ports 43 which open from the firing chamber 9b into a passage 44 in the plate 6. This passage 44 leads to the periphery of the plate 6 where another exhaust gas tube 45 is attached. The exhaust tubes 42 and 45 are joined to provide one exhaust gas outlet pipe 46 for the engine. This outlet pipe 46 may lead to a conventional muffler (not shown) if desired. The end plate 6 also has a passage 6c formed therein leading 60 from the carburetor pipe P to the intake manifold 26.

The sequence of operation is briefly as follows: Initial operation is begun by rotating the crank shaft 14 to cause the rock shaft 7 to move the pistons 8 and 9 to and fro. Initially this causes the pistons alternately to draw in 70 charges of fuel gas through their associated valve units and then to compress these charges and force them into the respective firing chambers 8b and 9b and finally to

compress the charges against the faces of the block 20. The spark plugs 24 and 25 are fired at the proper times to ignite these compressed charges. When a charge is fired by its spark plug, it expands against its piston and drives the piston down, thereby supplying power to compress another charge of fuel in the recess in the lower face of the piston around the valve unit therein. This also supplies power to the rock shaft 7 to rotate the crank shaft 14 and the engine begins to operate.

As each piston travels down, it first uncovers its exhaust ports 40 and 43 and then uncovers its fuel charge passages 36 or 38 so that the compressed fuel charge can flow into the firing chambers and push the exhaust gases out. To facilitate this action I provide ribs 47 and 48 on the tops of the pistons 8 and 9 to deflect the incoming gaseous fuel upward and keep it from flowing directly across the firing chamber to the exhaust ports 40 and 43. The faces of the block 20 are recessed to receive the ribs 47 and 48.

The pistons 8 and 9 are on a common hub 49 that is affixed to the shaft 7. Sealing around the pistons 8 and 9 and their hub 49 is accomplished by four sealing strips 50 in the outer face of each piston and springs 51 beneath the strips (see FIG. 10). These strips are pressed against the inner face of the cylinder. Similar strips 52 backed by springs 53 are interposed between the end plates 5 and 6 and the side faces of the pistons 8 and 9. The blocks 20 and 21 also carry sealing strips 54, 55 and 56. Because of the scale the springs backing up the strips are not shown in the main figures. However, the construction in the case of each of the strips 50, 52, 54, 55 and 56 is that shown in FIGURE 10. With this arrangement shown it is possible to force lubricant through a suitable aperture 57 in the end plate 5 and a similar aperture 58 in the end plate 6 and through similar apertures not shown in the blocks 20 and 21 to lubricate the bearing surfaces between the pistons and the stationary parts so that it is not necessary to mix any lubricant with the fuel as is commonly done in two cycle engines. The pistons actually do not touch the cylinder surface or the surfaces of the end plates. The seal strips ride these surfaces. If there is any blow-by of burned gases past the seals, this gas is arrested and forced back into the combustion chamber and kept out of the crankcase.

My invention provides a two cycle type of internal combustion engine with the following advantages:

(1) A push and a pull on the connecting rod due to the fact that alternate firing depresses first one piston then the other;

(2) Cylinder lubrication without mixing the lubricant with the fuel;

(3) A positive cam operated intake valve in contrast to the normal vacuum opened intake valve found in current two cycle engines;

(4) Suction intake of fuel through the intake valve with subsequent compression heating and mixing in a confined chamber back of the piston.

With my engine construction I obtain easy accessibility to all the parts. Removal of the end plate 5 provides access to all the chambers and the valves so they may be inspected. The valve units can be replaced in their entirety with ease. Each piston is moved down by explosion above it and is returned by force transmitted through the hub 49 from the other piston. Where direct drive rocking motion is desired it can be obtained from the shaft 7.

I prefer to air cool the engine. For this purpose the blocks 20 and 21 are hollow so air can flow through them. A shell 57 is mounted about the cylinder and secured thereto by screws 58 in bosses 59 on the cylinder 1. A fan 60 is mounted in spaced relation to the end plate 5 and coaxial with the shaft 7. This fan is driven by pulleys 61 and 62 and a belt 63. A conventional generator 64 is also driven by a pulley 65 and the belt 63. The pulley 61 is on the crank shaft 14.

The shaft portion 7a is supported by an internal bearing 66 on an end wall 67 at the back end of the base 2. The end wall 67, two curved side walls 68 and 69 and a partition wall 70 adjacent to the end plate 6, form a crank shaft well which has a removable cover 71. The hollow shaft 7 is thus supported internally by the bearing 66 and the drive arm 10 is clamped on the outside of the shaft 7 in such a way as to cut down the necessary overall length of the shaft 7. The hollow shaft 7 also serves to receive the bearing 72 for the shaft 73 of the fan 66, the bearing 72 having a flange 74 that bolts to the end plate 5. The partition wall 70 is clamped to the end plate 6 by a threaded portion 75 on the plate 6 and a nut 76.

It is believed that the nature of my invention will be clear from the foregoing description and the drawings.

Having described my invention, I claim:

1. In an internal combustion engine:
a rock shaft having fixed thereon piston members projecting outwardly from the shaft and away from each other;
a casing surrounding the pistons and providing chambers in which the pistons oscillate about the axis of the shaft;
a valved intake passage into each chamber below its piston for admitting gas for combustion;
a device in each chamber above each piston for igniting a gaseous fuel charge therein;
said casing having by-passes therein for conducting gas admitted below each piston around the piston into the respective chamber above the piston when the piston is at the low point of its oscillation in the chamber;
said casing having exhaust passages therein for conducting the gases of combustion out of the chambers; and
each valved intake passage being through a valve seat unit that projects into the respective chamber, the pistons being recessed in their lower faces to receive the valve seat units.
2. In an internal combustion engine:
a rock shaft having fixed thereon piston members projecting outwardly from the shaft and away from each other;
a casing surrounding the pistons and providing chambers in which the pistons oscillate about the axis of the shaft;
a valved intake passage into each chamber below its piston for admitting gas for combustion;
a device in each chamber above each piston for igniting a gaseous fuel charge therein;
said casing having by-passes therein for conducting gas admitted below each piston around the piston into the respective chamber above the piston when the piston is at the low point of its oscillation in the chamber;
said casing having exhaust passages therein for conducting the gases of combustion out of the chambers; and
said casing comprising a shell encircling said shaft and a pair of end plates closing the shell and having bearings therein for said shaft, said by-passes being in one of the end plates and the exhaust passages being in the other end plate.
3. In an internal combustion engine:
a rock shaft having fixed thereon a pair of oppositely directed piston members projecting radially from the shaft;
a casing surrounding the pistons and having upper and lower partition means dividing the space between the shaft and said casing into quadrant shaped chambers in which the pistons oscillate about the axis of the shaft;
a valve unit in the lower portion of each chamber including a spring closed valve;

push rods extending through the lower partition means for opening said valves;
a device in each chamber above each piston for igniting a gaseous fuel charge therein;
said casing having by-pass passages therein for conducting gas from below the pistons into the chambers above the pistons when the pistons are in their lower-most positions in their respective chambers;
said casing also having exhaust passages opening from the chambers outward at a level to be uncovered in the downward movement of the respective piston just prior to its reaching its lowermost position;
the outlets of the by-pass passages being on the opposite side of the chamber from the exhaust passages.

4. The device defined in claim 3 wherein the pistons have on their upper faces deflections operable to deflect the incoming gases upwardly whereby to force exhaust gases in the upper parts of the chambers down toward the exhaust passages.

5. The device defined in claim 3 wherein the pistons have grooves along their side faces and outer faces and spring-backed sealing bars are seated in said grooves and bear against the chamber walls.

6. The device defined in claim 3 wherein the casing is a shell having a cylindrical interior surface, and a pair of end plates closing the ends of the shell and having bearings therein for said shaft;

and the partition means comprises blocks removably secured to the shell and the end plates and carrying the valve units.

7. The device defined in claim 3 wherein each valve unit projects into the respective chamber and wherein the pistons are recessed in their lower faces to receive the valve units.

8. In an internal combustion engine:
shaft means having fixed thereon piston members projecting outwardly from the shaft and away from each other;

30

35

a casing surrounding the pistons and dividing chambers within which the pistons oscillate about the axis of said shaft means;
a valved intake passage into each chamber below its piston for admitting gas for combustion, said valved intake passage being through a valve seat unit that projects into the respective chamber, the pistons being recessed in their lower faces to receive the valve seat units;
means in each chamber above each piston adapted to ignite a gaseous fuel charge therein;
said casing having bypasses therein selectively opened and sealed by the position of each piston relative to the casing, said bypasses being adapted to intermittently conduct gas from below each piston into the respective chamber above the piston;

said casing having exhaust passages therein for conducting the gases of combustion from the chambers above said pistons after ignition.

9. The device defined in claim 8 wherein the exterior walls of said valve seat unit are complementary to the interior recess of the piston within which it is received so as to allow gases admitted through said valve seat unit to be compressed by downward movement of the piston over the valve seat unit.
